UNITED STATES PATENT OFFICE.

WILLIAM JOHN FAUNT, OF SAUSALITO, CALIFORNIA.

FENCE-POST.

1,125,827.

Specification of Letters Patent. Patented Jan. 19, 1915.

Application filed March 26, 1912. Serial No. 830,827.

To all whom it may concern:

Be it known that I, WILLIAM J. FAUNT, a citizen of the United States, and a resident of Sausalito, in the county of Marin, State of California, have invented a new and useful Improvement in Fence-Posts, of which the following is a specification.

My invention is an improvement in fence posts of the metallic type, and has for its object the provision of a simple, inexpensive post of the character specified, adapted for holding any number of wires, and wherein the holding means is concealed and covered to prevent tampering therewith.

In the drawings: Figure 1 is a side view of the post in place; Fig. 2 is a partial vertical section at the upper end of the post; Figs. 3 and 4 are sections on the lines 3—3 and 4—4, respectively, of Fig. 1; and Fig. 5 is a perspective view of the locking rod.

The present embodiment of the invention comprises a tubular body 1, circular in cross section, and tapering toward its upper end, the post being formed from a sheet of metal bent into form and with the edges 2 and 3 of the sheet lapping at the front of the post. The edge 2 of the sheet (Fig. 3), is lapped on the inner face of the sheet and is secured to the sheet near the opposite edge 3 by means of rivets 4. The edge 3 is lapped on the outer face of the sheet and is secured to the sheet by rivets 5. The series of rivets 4 are spaced apart from the series 5, and between the series the edge 3 of the sheet is shaped to form a chamber or passage 6 extending longitudinally of the post. The sheet between the series of rivets 4 and 5 is bent outwardly and then inwardly to form an external rib or ridge 7, the passage 6 being inside the rib, and the said rib and passage extending from the top of the post to a point below the ground level when the post is set. A cap 8 of semi-spherical form is arranged at the top of the post, and the said cap is provided with a tubular extension 9 on its flat face, which fits inside the upper end of the post and is secured to the post by means of rivets 10. The cap is of greater diameter than the post so that a portion thereof overhangs the post as shown at 11 in Figs. 1 and 2. This overhanging portion is of sufficient depth to cover the upper end of the rib 7 and passage or chamber 6, as shown in Figs. 1 and 2, and the said rib is provided with a series of spaced transverse notches or recesses 12, each of

which intersects the passage or chamber 6. The notches or recesses 12 are spaced apart in accordance with the spacing of the fence wires 13, and each notch or recess is adapted to receive one of the said wires. The notches 12 extend the full depth of the rib, as shown more clearly in Fig. 2 so that the wires 13 rest against the edge 2 of the sheet. A locking rod 14 is arranged in the passage 6 for holding the wires 13 in place in the notches, the said rod being between the wires and the outer side of the passage. The upper end 15 of the rod is bent laterally inward and passes through registering radial openings 16 and 17 in the post wall and extension 9, and the inner end of the rod is then bent downward, as shown at 18. Below the ground level 19 the wire holding means is not necessary, and that portion 20 of the side edge 3 of the sheet forming the post below the lower end of the rib 7 is separated from the upper portion, as indicated at 21, and is laid flat on the side edge 2, as shown in Fig. 4, and secured by rivets 22. The rod 14 is extended below the lower end of the rib 7 and is bent outwardly, as shown at 23, Fig. 4. The post is also braced at its lower end by a plate 24 arranged diametrically of the post with its wide dimension vertical. The ends 25 of the plate are bent laterally and secured to the sheet by rivets 26.

That portion of the post below the ground level is provided at irregular intervals with struck up spurs or lugs 27, each lug being triangular in shape. The lugs are formed by two slits meeting at an angle, the material between the slits being bent inwardly or outwardly. The lugs by their engagement with the soil assist in holding the post in the ground, and it will be obvious that the length of the rib 7 and the spacing of the notches 12 will depend upon the length of the fence and the arrangement of the wires.

The post is preferably of sheet steel, galvanized to prevent oxidization, and the steel will be of a thickness depending upon the conditions to be met. The diameter at the top will be about one-half that of the bottom and the post may be of any desired length. The joints are also preferably brazed, and it will be evident that the post might be cast instead of bent to shape.

The posts may be marketed without the notches 12, and the said notches may be cut with a suitable tool after the post is set, and

additional notches may be cut at any time after the post is set. The cap may also be omitted, if desired, and the shell of the post might be filled with plastic material capable of hardening.

5 The cap may be of wood or any other material, having a plug or solid extension 9, instead of the tubular extension shown.

When the soil is of suitable nature, the post 10 may be driven into the ground, and a driving cap may be used for this purpose if advisable for any reason.

After the cap is placed, the holding rod is entirely inclosed, so that there is but little 15 liability of the same being withdrawn by unauthorized persons. The lower end of rib 7 is extended below the ground level, in order that the lower end of the rod may be hidden.

20 The post may be set in concrete, if desired, and the notches 12 may be cut on an incline if necessary to receive the wires without bending, as in woven wire fencing.

I claim:

25 A tubular fence post of tapering form, and having a hollow longitudinally ex-

tending rib forming a passage on the outer face of the post from the small end or top thereof to below the ground level, the rib being provided with spaced transverse 30 notches for receiving the fence wires, a holding rod in the rib on the opposite side of the wires from the post, the notches for the wires extending the full depth of the rib, and the holding rod being of such diameter that it will press the wires in the notches laterally against the post, a cap having a reduced portion fitting within the upper end of the post and extending above the upper end of the rib and closing the 40 same, and a cross pin passing through the upper end of the post and the reduced portion of the cap, the post having a notch at the upper end of the holding rod to permit the rod to be bent over into the post, and the lower end of the rib being open to permit the locking rod to be driven into the ground.

WILLIAM JOHN FAUNT.
